UNITED STATES PATENT OFFICE

WILLIAM A. BOHNE, OF PHILADELPHIA, PENNSYLVANIA, ASSIGNOR TO E. F. HOUGH-
TON & COMPANY, OF PHILADELPHIA, PENNSYLVANIA, A CORPORATION OF PENN-
SYLVANIA

PRESS FOR MOLDED LEATHER ARTICLES

Application filed November 26, 1927. Serial No. 235,895.

This invention relates primarily to improvements in the methods of manufacturing molded leather articles such as washers or packing elements, and the principal object 5 of the invention is to provide means for facilitating the process of manufacturing such articles.

To this end, the invention contemplates provision of a novel form of cooling press 10 whereby the leather article, after the initial operation in which the leather blank is molded to desired form, may be rapidly cooled and set in its final form and condition.

More specifically, the invention contem- 15 plates the provision of a novel form of press adapted to receive the molded article from the molding machine in relatively soft condition, and in which the molded element is subjected to a rapid cooling operation, while 20 being maintained in its proper molded form.

The invention further resides in certain novel structural features of the aforesaid cooling press, as hereinafter set forth and as illustrated in the attached drawings, in 25 which:

Fig. 1 is a plan view of a press made in accordance with the present invention;

Fig. 2 is a front elevation of the machine, partly in section, on the line 2—2, Fig. 1;

Fig. 3 is a rear elevation of the press;

Fig. 4 is a fragmentary section on the line 4—4, Fig. 3, and

Fig. 5 is a fragmentary sectional view of the die elements and immediately associated 35 parts illustrating their relative positions during the cooling operation.

With reference to the drawings, the press in a preferred form may constitute a lower 40 relatively fixed housing 1, from each side of which extends a threaded rod 2 which together form a support for an upper die carrier 3 and which constitute also guides on which is slidably held a lower die carrier 4. The lower die carrier 4 has attached to the 45 under side thereof a pair of plungers 5—5, which operate in cylinders 6—6 in the housing 1. Power may be applied to the lower ends of the cylinders 6 through a pipe 7 to elevate the piston and with it the die carrier 4, and a reverse movement of these parts

may be obtained by applying power to the opposite ends of the cylinders 6 through a pipe 8. These pipes may be associated with a suitable source of fluid pressure, and may be controlled by suitable valves (not shown) 55 in obvious manner.

Threaded into the die carrier 3 is a plurality of die-carrying studs 9 adjustable vertically and retained in position in the present instance by nuts 10. Threaded into the lower end of each of the studs 9 is an adapter element 11 having at its lower end a projecting stud 12 onto which the male die elements 13 are threaded, as shown in Fig. 2.

Supported on the lower die carrier 4 is 65 a member 14 having at its edges an upstanding continuous flange 15 forming a receptacle in which are mounted female dies 16 adapted and positioned to cooperate respectively with the male dies 13 suspended from 70 the upper die carrier. In the present instance, the female dies 16 are detachably secured in the receptacle 14 by means of clamps 17, see Figs. 1 and 2. Annular projections 18 in the floor of the receptacle 14 fit into correspondingly formed grooves or recesses in the under sides of the dies 16 and with the clamps 17 function to retain these dies firmly fixed 75 in proper alignment with the respective corresponding male dies 13. In the present instance, the member 14 is located and maintained in position upon the die carrier 4 by 80 dowels 19.

From the foregoing description, it will be apparent that when power is applied 85 through the pipe 7, the pipe 8 functioning at the time as an exhaust for the upper ends of the cylinders 6, the plungers 5 will be forced upwardly in the cylinders and will elevate the lower die holder 4, thereby bringing the female dies into operative relation 90 with the relatively fixed male dies 13 on the upper die carrier. Stops are provided in the form of nuts 20 on the rods 2 to limit the upward movement of the lower die carrier 4 so that desired maximum pressure may be applied to the leather elements in the dies, as hereinafter set forth.

Referring now particularly to Fig. 3, it will be noted that provision is made in the 100

form of a duct 21 for introducing a cooling liquid to the receptacle 14. In the present instance, a part of this duct 21 is secured to the housing 1. This part includes a valve 22 which controls the flow of the fluid through the duct. The duct 21 includes also a portion attached to the lower and in the present instance movable die carrier 4, and an intermediate flexible section 23 to permit the movement between the relatively movable parts. As shown in Fig. 3, the upper end of the duct 21 is made in the form of a goose neck 24.

The valve 22 is adapted to be opened automatically when the die carrier 4 is elevated, in the manner previously described, to admit a cooling fluid to the receptacle 14. For this purpose, I provide an operating lever 25 pivoted at 26 to a bracket 27 on the valve body. The inner end of the lever 26 engages the stem 28 of the valve. The outer end of the lever 25 is connected through a spring 29 with the lower die carrier 4. When this carrier is in the normal depressed position, as shown in Fig. 3 of the drawings, the valve 22 is closed, and when the die carrier is elevated, it will be apparent that the lever 25, through the connecting spring 29, is actuated to depress the stem 28 thereby opening the valve 22 and admitting water to the receptacle 14. So long as the die carrier 4 remains elevated, the cooling liquid continues to flow into the receptacle.

In order to prevent overflow of the cooling liquid, I provide in the receptacle an overflow pipe 30, see Fig. 3, this pipe extending upwardly to a point short of the upper edge of the flange 15 and having also near the floor of the receptacle a series of relatively small apertures 31. The overflow pipe 30 is connected through a flexible duct 32 with a pipe 33 through which the escaping liquid may discharge. The overflow 30 is of such capacity as to maintain the liquid in the receptacle at the desired level during the period of flow through the pipe 21. When the die carrier 4 is lowered to the normal position, as shown in the drawings, the small apertures 31 function as bleeds to completely empty the receptacle 14. By this means, not only is a desirable circulation of the cooling liquid through the receptacle and around the female dies maintained during the periods that the die carrier 4 is elevated, but at each successive elevation of the die carrier from the normal depressed position the receptacle is empty and in condition for reception of an entirely new and fresh body of the cooling liquid.

The press illustrated in the present instance is adapted for the cooling of flange packings of the general form illustrated in section in Fig. 5, which shows the lower die holder 4 at the top of its travel bearing against the stops 20. In this position, as

clearly illustrated, the dies are in operative relation and are effective to hold under desired compression the previously formed flange packing 34. In operation, the flange packing in relatively soft condition is taken from the molding press which may be of any desired or standard form, and is placed in the female die 16 of the cooling press which is then in the depressed or inoperative position. Power is then applied to elevate the die carrier 4 which brings the female die and the contained packing element into operative relation with the male die, as shown in Fig. 5. Simultaneously with the elevation of the carrier 4, water is admitted to the receptacle 14 through the pipe 21, as previously described, flowing around the female dies and circulating freely by reason of the overflow 30. The parts are maintained in this relative position until the leather packing elements are cooled and set in their desired form, after which pressure is applied through the pipe 8 to the upper ends of the cylinders 6 to cause the lower die carrier 4 to be depressed. With the depression of the die carrier 4, the flow of liquid through the pipe 21 is interrupted and the overflow apertures 31 come into effect to entirely empty the receptacle 14 as previously described.

In order to facilitate the extraction of the cooled leather packings from the female dies, I provide each of these dies with an ejector element consisting of a rod 35 projecting through the bottom of the receptacle 14 and centrally into the die, as illustrated in Fig. 2. In the present instance, the aperture in the bottom of the receptacle through which the rod 35 extends is sealed against leakage by means of packing 36 forced into a countersunk recess around the rod 35 by a threaded gland 37. The rod 35, which is adapted to slide through this packing box, projects downward through the lower die carrier 4 and beyond the bottom thereof so as to engage a relatively fixed part of the housing 1 when the die carrier is depressed, the rod 35 thus being elevated against the under side of the packing element 34, as illustrated in broken lines in Fig. 2, and forcing the latter upwardly from the die, at least to an extent rendering withdrawal relatively easy. The extent of the effective thrust of the ejector element may be regulated by means of a bolt 38 threaded into the lower end of the rod. Provision is also made, as shown in Fig. 4, for limiting the movement of the ejector rod 35 and to prevent their rotation, this consisting in the present instance of a longitudinal slot 39 in the said rod into which projects the inner end of a bolt 40 threaded into the die carrier 4.

It will be apparent that the machine may be modified in details without departure from the essential features of the invention.

I claim:

130

1. In a cooling press for molded leather articles, the combination with a relatively fixed housing, of an upper die carrier fixed to said housing, a lower die carrier movable in the housing, cylinders in the housing, plungers in said cylinders connected to the movable die carrier, means for introducing fluid pressure to the cylinders, a receptacle mounted on the movable carrier, a female die mounted in the receptacle and cooperative with the male die to maintain the molded article in the desired molded form, a valve-controlled duct entering said receptacle, overflow means in said receptacle for discharging therefrom any excess liquid entering through the said pipe, and automatic means for opening the valve to admit the cooling medium to the receptacle when the movable die carrier is advanced to bring the dies into operative relation and for interrupting the flow of said medium when the movable die carrier is retracted.

2. In a cooling press for molded leather articles, the combination with a relatively fixed housing, of an upper die carrier fixed to said housing, a lower die carrier movable in the housing, cylinders in the housing, plungers in said cylinders connected to the movable die carrier, means for introducing fluid pressure to the cylinders, a receptacle mounted on the movable carrier, a female die mounted in the receptacle and cooperative with the male die to maintain the molded article in the desired molded form, a valve-controlled duct entering said receptacle, overflow means in said receptacle for discharging therefrom any excess liquid entering through the said pipe, automatic means for opening the valve to admit the cooling medium to the receptacle when the movable die carrier is advanced to bring the dies into operative relation and for interrupting the flow of said medium when the movable die carrier is retracted, and means for emptying the receptacle of the cooling medium when the movable die carrier is retracted.

WILLIAM A. BOHNE.
